[57] CLAIM

The ornamental design for a bottle for a laboratory analyzer, as shown and described.

DESCRIPTION

FIG. 1 is a prospective view of a bottle for a laboratory analyzer showing our new design;

FIG. 2 is a front elevational view of FIG. 1;

FIG. 3 is a cross-sectional view of FIG. 5 taken along the line III—III;

FIG. 4 is a rear elevational view of FIG. 1;

FIG. 5 is a side elevation view of FIG. 1, the opposite side elevational view being a mirror image thereof;

FIG. 6 is a prospective view of a second embodiment of FIG. 1;

FIG. 7 is a front elevational view of FIG. 6;

FIG. 8 is a cross-sectional view of FIG. 10 taken along the line III—III;

FIG. 9 is a rear elevational view of FIG. 6; and,

FIG. 10 is a side elevational view of FIG. 6, the opposite side elevational view being a mirror image thereof.
